PUMP

Kurt Schoene, Hamburg, Germany

Application December 3, 1934, Serial No. 755,826
In Germany December 27, 1933

1 Claim. (Cl. 103—205)

This invention relates to plunger pumps, and particularly relates to means for guiding the plungers of vertical plunger pumps.

In a vertical plunger pump, it is desirable to 5 keep the overall height of the pump to the absolute minimum, in order to reduce the suction head. Where an ordinary trunk piston is used and mounted directly above the crank case, a number of difficulties are encountered. Water 10 leaking past the piston will pass to the crank case and become mixed with the oil which is highly objectionable, particularly where forced lubrication is adopted.

In such pumps it is customary to use a long 15 trunk piston and lubricate only the lower end of the piston, reliance being placed on the water to lubricate the upper end. Where clean water is being pumped this arrangement is objectionable because it is inevitable that a portion of the oil will come in contact with the water and 20 contaminate the same. On the other hand, where water containing grit or sand is pumped, a certain amount of grit is carried between the working surfaces of the piston and the cylinder so 25 that severe wear occurs, particularly in view of the side thrust exerted by the pitman or connecting rod. The primary purpose of the present invention is to avoid this difficulty.

The piston is of the trunk type, having a head 30 and skirt and works in a cylinder. The piston, however, is not guided primarily by the cylinder, but is rigidly connected to a cross-head which works in ways, whose upper end terminates within the skirt of the piston in all piston positions.

The cross-head is lubricated with oil, but 35 between the piston and the cylinder wall, reliance is placed on water lubrication. Because the upper end of the cross-head guides are within and above the lower margin of the piston skirt, there 40 is no possibility for the oil and water to become mixed. On the contrary, any water leaking between the piston and the cylinder drains away without entering the crosshead guides. Consequently no water can enter the crank case and no 45 oil can ever contaminate the water being pumped. Furthermore, the cross-head and guides take up the lateral thrust of the pitman so that even if some grit does penetrate between the piston and cylinder, the abrasive action will be kept to a minimum because the lateral thrust developed by 50 the pitman is not taken up between the cylinder and piston.

The invention is particularly adaptable to the type of pump having automatic discharge valves and inlet ports which are controlled by a re-

ciprocating sleeve valve, the inlet ports being so arranged as to deliver a portion of the kinetic energy of the entering water to the pump plunger. This type of pump is described and claimed in my U. S. Patent No. 1,760,171, issued May 27, 5 1930.

As thus embodied, the invention is illustrated in the accompanying drawing, in which the single figure is a vertical axial section through a pump cylinder and piston with guiding means 10 constructed according to my invention.

In this drawing only those elements which enter directly into the claimed combination are illustrated. Thus only the upper portion of the crank case is shown, it being understood that 15 according to common practice the crank case will enclose the crank shaft and crank. The upper end of the pump chamber and the discharge valves are omitted altogether, and only a portion of the main frame or housing is shown. 20

The crank shaft is indicated at 6 and the crank pin at 7. The orbit of the center line of the crank pin is indicated by the dot and dash line A. The connecting rod or pitman is indicated at 8. 9 represents the upper portion of the crank 25 case which is formed with an upstanding cylindrical cross-head guide member 11. The cylinder is indicated at 12 and is supported in a yoke 13 which is suspended by the webs 14 which are or may be formed integral with the upper portion 30 of the crank case. However formed, the members 14 are in fixed relation to the member 9. The inlet ports are indicated at 15, and the encircling sleeve inlet valve at 16.

Working in the cylinder 12 is a piston made up 35 of a head 17 with central hub 18 and a peripheral depending skirt 19. No packing rings or other packing means are shown, but if packing means are used they may conform to known practice without affecting the present invention. Slid- 40 able in the guide 11 is a cross-head which is structurally similar to a conventional trunk piston, that is to say, it has a head 21 and a pendant skirt 22, the skirt fitting within the guide 11. At the center of the head 21 is a hub 23 which abuts 45 the hub 18. A bolt 24 with nut 25 serves to hold the hubs 18 and 23 in assembled relation so that the cross-head and the piston reciprocate as a unit. The nut 25 is specially formed as shown to conform to the desired contour of the piston head. 50 In this respect it will be observed that features characteristic of my prior patent are included.

The parts are so arranged that as the piston reciprocates the lower margin of the skirt 19 is always below the upper end of the cross-head 55

guide 11 so that a portion of the skirt always encircles a portion of the cross-head guide and is spaced therefrom a substantial distance, as indicated in the drawing. The connecting rod or 5 pitman 8 is connected with the skirt portion 22 of the cross-head by means of a wrist pin, conventionally represented at 26, so located that as the cross head reciprocates the limits of travel of the wrist pin are well within the longitudinal limits 10 of guide 11.

It will be observed that as the crank is rotated the piston and cross-head will be reciprocated. The cross-head and its guide absorb the lateral thrust of the pitman 8 so that the pitman exerts 15 no lateral thrust upon the piston.

While leakage between the cylinder wall and the piston is not contemplated, if leakage occurs between the cylinder wall and the skirt 19 it will drain away, cylinder wall 12 being spaced from 20 the upper wall 9 of the crank case to permit this drainage flow.

Since the cross-head guide 11 is an upstanding cylinder it protects the guiding surface from contact with the water. Consequently no water 25 can come in contact with the oil which lubricates the cross-head in its guide and no water can enter the crank case. Similarly the oil which lubricates the cross-head in its guide can never come in contact with the working surface of the piston 30 skirt 19. In this way the working space of the pump is protected against entrance of lubricating oil. Therefore copious lubrication of the cross-head is permissible with the result that a close 35 guiding fit for the cross-head may be used. This insures the elimination of side thrust on the piston and minimizes the abrasive effect of such grit as may enter between the piston skirt and cylinder wall.

It will be observed that as a result of the construction above described, the height of the pis- 40

ton head above the wrist pin is little if at all increased as compared to a similar structure of conventional type using a long trunk piston or plunger. From this it follows that the overall height of the pump is not increased. 5

The actuating means for the sleeve valve 16 is not shown, not being a part of the present invention. The use of conventional means, such as eccentrics and eccentric rods, is contemplated. 10

While the invention is particularly intended for use in conjunction with the type of pump disclosed in my patent above identified, it is susceptible of use with pumps of other types, specifically, with pumps having conventional inlet and discharge 15 mechanisms.

What is claimed is,—

In a plunger pump for liquids, the combination of a substantially vertical cylinder; a member forming the upper portion of a crank case, rigidly connected with but spaced from said cylinder, and having a tubular cross head guide longer than the working stroke of the plunger extending upward to a point within the cylinder; a piston working in the cylinder and having a head, 20 and a pendant skirt, which skirt in all positions of the piston encircles and is spaced from the upper portion of said guide; a cross head working in said guide and connected with the head of said piston; a crank in said crank case; a pitman 25 connected with said crank; and a wrist pin connecting the pitman with the cross head, the length of the guides being so related to the throw of the crank, and the wrist pin being so located in the cross head that the limits of travel of the wrist pin are within the longitudinal limits of the 30 guide, and the piston head at its lower limit of motion closely approaches the upper end of the 35 guide.
